UNITED STATES PATENT OFFICE.

JOSEPH LAVOIE AND JEAN FRANCOIS CHAZOTTE, OF MONTREAL, CANADA,
ASSIGNORS OF ONE-THIRD TO ADJUTOR CARMEL, OF SAME PLACE.

EXTENSION FIRE-LADDER.

SPECIFICATION forming part of Letters Patent No. 635,440, dated October 24, 1899.

Application filed July 22, 1899. Serial No. 724,878. (No model.)

To all whom it may concern:

Be it known that we, JOSEPH LAVOIE, a citizen of the Dominion of Canada, and JEAN FRANCOIS CHAZOTTE, a citizen of the French Republic, both residing in the city and district of Montreal, Province of Quebec, Canada, have invented certain new and useful Improvements in Extension Fire-Ladders; and we do hereby declare that the following is a full, clear, and exact description of the invention, such as will enable others skilled in the art to which it appertains to make and use the same.

This invention relates to extension fire-ladders; and its object is to provide a ladder of this character which is of comparatively light weight and which can be extended to a great length.

A further object is to provide a ladder which is simple in construction, easily and quickly operated, and which can be manufactured at a moderate cost.

To these ends the invention consists in an extension fire-ladder constructed substantially as hereinafter illustrated and described, and defined in the appended claims.

Referring to the drawings, in which similar letters of reference indicate similar parts, Figure 1 represents a view in elevation of an extension fire-ladder constructed in accordance with this invention. Fig. 2 is a similar view looking from the rear of the ladder. Fig. 3 is a central vertical section thereof. Fig. 4 is a transverse section on the line 4-4 of Fig. 3; and Fig. 5 is a transverse section on the line 5-5 of Fig. 3, showing a detail of the construction.

In the drawings, A represents the carriage or wagon body upon which the ladder is supported and which may be of any usual or preferred form and is provided with suitable running-gear. Upon each side of the wagon-body is pivoted an extension a, which is adapted to be swung outwardly at an angle thereto and is provided upon its outer end with pivoted legs a', adapted to rest upon the ground and brace the wagon when the ladder is being operated. As shown in Fig. 1, the extensions a are adapted to be folded against the sides of the wagon and the legs a' folded up and supported upon suitable brackets a² in order that they may be out of the way when

the wagon is in motion and the ladder not in use. At the rear end of the wagon-body are secured one or more rods a³, which are preferably threaded in suitable sockets and are provided with operating-handles a⁴, by means of which they may be adjusted so as to bear firmly against the ground and prevent the wagon-body from tilting when the ladder is in use.

At a suitable point on the wagon-body is secured a base-plate B, which is provided with a flange b, having notches b'. Within the flange of the base-plate B is rotatably secured a turn-table B' by means of a centrally-arranged bolt b², and suitable friction-rollers b³ are interposed between the said base-plate and the turn-table, as is clearly shown in Fig. 3.

At opposite sides of the turn-table B is secured a suitable supporting-standard B², in the lower portion of each of which is journaled a crank-shaft b⁴, supported in suitable brackets. Upon the end of each of said crank-shafts is fixed a notched plate b⁵ and a pinion b⁶, which pinion meshes with a gear-wheel b⁷, fixed upon each end of the shaft b⁸, journaled in said standards B². Fixed upon said shaft b⁸ and located upon the inner sides of the standards B² are two pinions b⁹, each of which meshes with two gear-wheels b¹⁰ and b¹¹, fixed upon shafts b¹² and b¹³, journaled in the said standards.

Rotatably mounted upon a rod d are two segment-plates D, one adjacent to each of the supporting-standards B², and the peripheries of said plates are provided with gear-teeth meshing with the gear-wheels b¹⁰ and b¹¹. A plurality of perforations d' are provided in each of said plates D, which are adapted to be brought into alinement with a series of perforations d² formed in the standards B². A suitable lock-bar C is adapted to be passed through said openings when in alinement for the purpose of locking the said segment-plates in their adjusted position. The lock-bar C is preferably attached to a suitable chain C', which is secured to one of the standards B², and a series of hooks C² are secured upon the wagon-body to support said lock-bar when not in use.

To the upper portion of the segment-plates D is secured the frame E, which supports the

ladders F, and journaled in the lower parts of said frame is a shaft e, which is provided upon each end with a suitable crank-handle e', by means of which the said shaft may be 5 rotated.

Fixed upon the shaft e are the pinions e², which mesh with the gear-wheels e³, fixed upon the side of the winding-drums e⁴, of which there are preferably two, one being fixed upon 10 each end of the shaft e⁵, journaled in a bracket e⁶, secured to each of the frames E, as is clearly shown in Figs. 1 and 3. Upon the outer sides of each of the said frames E is fixed to the shaft e⁵ a ratchet-wheel e⁷, the teeth of which 15 are adapted to be engaged by a spring-pressed dog e⁸ for preventing the backward rotation of the drums e⁴, as is clearly shown in Fig. 1.

The frames E are provided with a groove e⁹, which forms a guideway for the lower section 20 f of the ladder F and prevents the accidental displacement thereof. Each of the ladder-sections f is provided upon one face with a tenon f', which is adapted to fit into the groove f² formed in the other face of said sections, 25 whereby each section is adapted to slide or telescope one upon the other and at the same time is prevented from accidental displacement. The last section f³ is formed of a flat strip and is held within the groove f² of the 30 preceding section by means of a lip f' formed thereon, as shown in Fig. 5.

A suitable rope or cable G is wound around the drums e⁴ and is passed about a series of pulleys g, secured to the upper and lower portions 35 of each of the ladder-sections f and secured to the lower portion of the last ladder-section f³, as is clearly shown in Fig. 3. It is evident from the above description that by suitably rotating the drums e⁴ by means of 40 the crank-handles e' the ladder-sections f and f³ may be extended to any desired extent or telescoped upon each other until they all rest upon the frame E, as shown in Fig. 3.

A suitable lock-bar H is pivoted at each end 45 upon the outside of each of the standards B², and a downwardly-depending lug h, formed upon each side of said lock-bar, is adapted to engage with the notches of the plates b⁵, and thus prevent the accidental rotation of 50 the shafts b⁴. The central portion of the lock-bar is provided with a lug h', which is adapted to be engaged by an opening h² in the vertically-arranged rod h³, which is pivoted upon the turn-table B'. A locking-dog h⁴ is pivoted to the standard B² and is adapted to bear 55 upon the upper side of the lock-bar H to hold the lug h firmly in engagement with the notches of the plate b⁵. A suitable link connects said dog h⁴ with the rod h³, whereby the 60 movement of said rod raises the said dog up out of engagement with the lock-bar H at the same time the said lock-bar is released.

A lock-bar H', similar in construction to the lock-bar H, is pivoted to the sides of the standards B² near the bottom thereof, and an outwardly-extending lug h⁵ is formed centrally thereon, which serves as a handle and also to

engage the notches b' of the base-plate, and thus hold the turn-table from accidental rotation. 70

Upon the front portion of the wagon-body is secured a suitable reel J, carrying the hose J', the nozzle of which is secured in any suitable manner to the outer end of the section f³ of the ladder F, as shown in Fig. 1. The 75 section f³ of the ladder may be provided with a suitable guard J², if desired, to prevent accident to the firemen. Suitable brace-rods K are secured to the front of the wagon to sustain the weight of the ladders when not in 80 use, as shown in Fig. 1.

Upon reaching the scene of the fire the wagon is drawn up to a convenient point and the braces placed in position. The turn-table is then adjusted so as to bring the ladders 85 in the best position and then locked. The ladders are now properly inclined by turning the crank-handles b' and the lock-rod C placed in position. The ladder-sections are then extended by operating the crank-handles e', carrying with them the hose, and the apparatus 90 is ready for the firemen to ascend.

While we have herein shown a preferred form of carrying our invention into effect, yet we do not desire to limit ourselves to such 95 preferred details of construction, but claim the right to use any and all modifications thereof which will serve to carry into effect the objects to be attained by this invention in so far as such modifications and changes 100 may fall within the spirit and scope of our said invention.

We claim—

1. The combination with a suitable wagon-body, of a base-plate secured thereon; a turn-table rotatably secured upon said base-plate; supporting-standards secured to said turn-table, a locking-lever pivoted to said standards and adapted to engage notches formed in said base-plate, for locking the turn-table 110 in its adjusted position; a supporting-frame adjustably pivoted to said supporting-standards; locking mechanism, substantially as described, for locking said frame in its adjusted position; an extensible ladder mounted upon 115 said supporting-frame; and mechanism, substantially as described, mounted upon said supporting-frame, for extending and retracting said ladder, substantially as described.

2. The combination with a suitable wagon-body, of a base-plate secured thereon; a turn-table rotatably secured upon said base-plate; supporting-standards mounted upon said turn-table; a locking mechanism, substantially as described, for locking the turn-table 125 to the base-plate in its adjusted position; geared segments rotatably mounted in said standards; an operating-lever; a train of gearing connecting said lever with said segments, a locking mechanism substantially as described for retaining said segments in their 130 adjusted position; a supporting-frame secured to said segments; an extensible ladder mounted in said frame; and mechanism, sub-

stantially as described, mounted upon said frame, for extending and retracting said ladder, substantially as described.

3. The combination with a suitable wagon-
5 body, of a supporting-frame adjustably mounted thereon; mechanism, substantially as described, for retaining said frame in its adjusted position; a plurality of ladder-sections slidably mounted upon said supporting-frame;
10 an operating-shaft journaled in said frame; a winding-drum mounted upon said frame; a train of gearing connecting said drum with said operating-shaft; a locking mechanism, substantially as described, for preventing the
15 backward rotation of said drum; a plurality

of pulleys secured to said ladder-sections; and a cord or cable connected with said drum and passing through said pulleys, the end of said cord being attached to the outer ladder-section, whereby the ladder-sections are 20 adapted to be extended and retracted, substantially as described.

In witness whereof we have hereunto set our hands in the presence of two witnesses:

JOSEPH X LAVOIE.

JEAN FRANCOIS CHAZOTTE.
